UNITED STATES PATENT OFFICE

2,200,066

GAS PRODUCER OF THE ROTARY GRATE
TYPE

Karl Koller, Budapest, Hungary

Application December 14, 1938, Serial No. 245,577
In Germany December 27, 1937

7 Claims. (Cl. 48—66)

My invention relates to gas producers, more especially of the rotary grate type fitted with cutter members. It is an object of this invention to improve this type of producer with a view to avoiding obstructions of the ash-pan by deposits forming thereon, and irregularities in the discharge of the slag whereby the operation of the gas producer might be hampered.

Gas producers of the rotary grate type with cutter members are well known (see British Patent 7,330 of 1911). The main features of these gas producers consist in this, that below the shell of the gas producer a rotatable, water-filled ash-pan is provided, the slightly coned bottom of which carries in the middle a nozzle-like grate and, extending from the middle towards the periphery, a plurality of curved transporting and shearing cutters, so-called milling cutters, having an inclined working surface, which operate uniformly on the whole of the bottom surface of the fuel column and displace the slag towards the periphery. From the ash-pan the displaced slag is removed by means of a plough-like scraper member which is fixed to a submerged ring which is rigidly connected to the lower end of the gas producer shell and extends into the ash-pan. According to a further proposal by the applicant (see British Patent 236,725) stemming members, so-called stemming shears, are provided on the outside of the submerged ring, the lower edge of which members together with the upper edges of the milling cutters exert a shearing action on the lumps of slag in a plane parallel to the bottom of the ash-pan.

These gas producers have been found to work very well in practice and are in use in a great number of works, giving excellent results. It has been found, however, that in some circumstances a cement-like deposit may form on the bottom of the ash-pan between the milling cutters, which in the first place reduces in an unfavorable manner the space in which the milling cutters operate and may in time when the plant is in continuous operation grow to such an extent that the operation of the milling cutters is entirely obstructed, resulting in a reduction in the capacity of the gas producers and a disturbance of the gasification process.

This undesirable phenomenon may be accounted for as follows: During the charging of the gas producers a sorting of the coal according to its size of grain takes place, the larger pieces of coal sliding towards the shell of the gas producer, whilst the coal dust falls down in the middle. This distribution of the coal according to

the size of grain remains unchanged in the fuel column during its passage through the gas producer, so that, after the formation of slag in the lower part of the gas producer, the fine ash slides down in the middle part and the larger pieces of slag on the outer part of the ash-pan bottom. With kinds of coal which contain much dust and the ash of which, owing to its chemical composition, shows a tendency to bind hydraulically, it frequently occurs that the fine ash formed from the coal dust and sliding down in the middle becomes bound under the influence of the water contained in the ash-pan, so that it hardens as a solid deposit between the milling cutters.

A further disadvantage of these gas producers, which has often been observed, consists in this that the discharged slag contains large lumps. The reason for this is, that the larger pieces of slag are exposed during the coaction of the stemming members with the milling cutters to a shearing action only in an approximately horizontal plane. They are thus cut up in an irregular manner, in accordance with the manner in which they lie between the coacting edges, which may result in irregularities in the discharge of the slag and consequently in the operation of the gas producer.

The main object of the invention is to overcome these disadvantages of the rotary grate gas producers operating with milling cutters, described above. For this purpose the milling cutters, which preferably have a vertical operating surface, are according to the invention arranged only at the periphery of the raised middle part of the ash-pan bottom, which has the form of a steep surface of revolution, each being provided with a vertical shield. Furthermore, the stemming shearing members are disposed in such a manner at the inside of the wall of the submerged ring that their edges coat both with the vertical edges of the shields and also with the inclined edges of the milling cutters, whereby the pieces of slag are subjected during the rotary motion of the ash-pan to a shearing and breaking action in a vertical and in an inclined plane.

The rotary surface forming the middle part of the ash-pan bottom may have the form of a straight or of an inwardly curved cone-like surface or may consist of two conical surfaces, the inner one of which is steeper than the outer one.

The invention also has for its purpose to overcome the disadvantage of the rotary grate gas producers operating with milling cutters, that the resistance of the material increases consider-

ably in front of the scraper member which is fixed to the immersed ring, whilst behind this member it suddenly drops, so that at the last named place considerably more material emerges 5 from the gas producer than at the other places, which may lead to the coal column sinking in an irregular manner in the gas producer and to the fire becoming inclined. In order to avoid this undesirable phenomenon as well, according to a 10 further modification of the invention the discharging space of the ash-pan is in the region of the scraper member separated from the interior of the gas producer by a partition which extends parallel to the submerged ring.

15 The details and the manner in which the gas producer according to the invention operates shall now be more particularly described with reference to the accompanying drawing, showing by way of example and in a purely diagrammatic 20 manner, an embodiment of my invention, in which

Fig. 1 is a longitudinal section through the gas producer,

Fig. 2 a cross-section of the same on the line II-II of Fig. 1,

25 Fig. 3 is a portion of Fig. 1 with the milling cutters and shields and the stemming shearing members, drawn to a larger scale, and

Fig. 4 is a section on line IV-IV of Fig. 3.

Referring to the drawing, the gas producer 30 consists as usual of a shell 1 with a cover plate 2, a charging device 3 and an outlet branch 4, also of a submerged ring 4 which is fixed to the lower end of the shell and extends into an ash-pan 6 which is rotatable by means of the drive 5 and 35 supports the nozzle-like grate formed of rings 7. To the grate is connected the supply pipe 8 for the gasifying means.

According to the invention the middle part of 40 the ash-pan bottom has the form of a steep surface of revolution, the generating lines of which, at least in the middle part of the gas producer, that is in the region of the fine ash, are inclined at an angle of about 45°. In the example shown, it consists either of two conical surfaces 10 and 45 11 (see lefthand half of Fig. 1), of which the inner one is steeper than the outer one, or of an inwardly curved cone-like surface 12, (see righthand half of Fig. 1). At the outer part of the surface of revolution, for instance in the first-named arrangement at the less steep conical surface 11, the short milling cutters 13 are provided, which extend to below the immersed ring, consist of vertical plates bent for instance in accordance with a logarithmic spiral and are offset at 50 14. Fitting closely to the offset part of the milling cutters are the upwardly extending shields 15 formed by vertical plates, which are fixed to the milling cutters, for instance by means of screws 16. The shields 15 are shorter than the milling 55 cutters 13, so that there is a gap between the vertical inner edges of the shields and the inside of the wall of the immersed ring 4. Between the upper edges of the milling cutters and the lower edge of the immersed ring there is also a gap.

To the inside of the wall of the immersed ring are fixed at the bottom the stemming shearing members 18 which consist for instance of pieces of flat iron with the bottom edge bent over and which extend at the top to about the upper edge 70 of the shields. These stemming bodies are so dimensioned and arranged that they fit into the aforesaid gaps, so that during the rotary motion of the ash-pan the milling cutters together with the shields can be moved past them. Preferably the number of stemming bodies differs from that

of the milling cutters by one, that is to say, if there is an even number of milling cutters, there is an uneven number of stemming bodies. To the immersed ring is also fixed the scraper member 19 with a deflecting plate 20. In the region of 5 the scraper member the discharging space of the ash-pan is separated from the interior of the gas producer by the partition 21 which is fixed to the immersed ring by means of ribs 22.

The gas producer according to the invention 10 operates in the following manner: The fine ash formed in the middle part of the gas producer slips down on the steeply inclined bottom 10 or 12 of the rotating ash-pan under the action of 15 the coal column resting on it and is carried along by the sliding down larger lumps of slag which are formed in the outer zones of the gas producer, and which are themselves displaced by the milling cutters 13 out of the space within the gas producer and are broken up by the shearing and 20 breaking action of the coacting edges (indicated in Fig. 3 by somewhat heavier lines) of the stemming plates 18 and the shields 15 and the milling cutters 13 respectively. As will be seen from Fig. 25 3 the coacting shearing edges have an L-like form, that is to say the cutting action takes place both in a vertical and in an inclined plane, resulting in a uniform breaking up of the slag. The displaced and uniformly broken up slag falls on to the flat 30 peripheral part of the ash-pan bottom, from which it is discharged by the scraper member 19. The discharged slag is prevented from falling back into the interior of the gas producer by the partition 20.

As will be seen from the above description of 35 the mode of operation of the arrangement illustrated, the problems put forward at the beginning of the specification are completely solved. The fine ash reaching the steep part of the ash-pan bottom can slide down unhindered on the same, 40 during which it cannot become bound, as it does not come in contact with water. It can also not accumulate between the milling cutters, as these cutters are arranged only at the periphery of the steep part of the ash-pan bottom, that is in the 45 region of the larger pieces of slag, where there is no danger of an accumulation of slag. In this region the fine ash is necessarily carried along by the larger pieces of slag, so that it can no longer have any detrimental effect.

Furthermore, through the coaction of the shields and the milling cutters on the one hand and the stemming bodies on the other hand a uniformly broken up slag is obtained, which favorably affects both the gas producing process and 55 also the discharge of the slag and also facilitates the further disposal of the slag. The arrangement of the partition described also has a considerable share in rendering the gas producer process uniform.

Finally, owing to the fact that the number of 60 milling cutters differs from that of the stemming bodies suitably by one, only a single pair of shearing and breaking elements will at any time be operative, so that the resistance which occurs during the breaking up of the slag is effective only at one place at a time. Should the 65 number of the two elements be equal, all the pairs of shearing and breaking elements would operate at the same time, which would result in the work 70 of breaking up the slag being considerable greater.

I wish it to be understood that I do not desire to be limited to the exact details of construction shown and described, for obvious modifications will occur to a person skilled in the art.

I claim:

1. A gas producer comprising in combination, a rotatable water-filled ash-pan, milling cutters and a submerged ring extending into said ash-pan, a scraper member and a plurality of stemming shearing members on said ring, said milling cutters being arranged only at the periphery of the middle part of the ash-pan bottom, which has the form of a steep surface of revolution, a vertical shield on each milling cutter, said shear members being so arranged on the inner wall of said ring that their edges are free to coact both with the vertical edges of said shields and with the inclined edges of said milling cutters.
- 10 2. The gas producer of claim 1, in which said milling cutters have a vertical working surface.
- 15 3. The gas producer of claim 1, in which the middle part of the ash-pan bottom has the form of a straight cone-like surface.
- 20 4. The gas producer of claim 1, in which the

ash-pan bottom has the form of an inwardly curved cone-like surface.

5. The gas producer of claim 1, in which the middle part of the ash-pan bottom consists of two conical surfaces, which surfaces are continuous with respect to each other of which the inner one is steeper than the outer one, while the milling cutters are arranged on the outer conical surface.

6. The gas producer of claim 1, in which the shields are fixed on the milling cutters and the milling cutters extend below the submerged ring in such manner that a gap is left between their outer edges and the submerged ring.

7. The gas producer of claim 1, in which the number of milling cutters differs by one from the number of stemming shearing members.
